UNITED STATES PATENT OFFICE.

NIELS NIELSEN, OF PITTSBURG, CALIFORNIA.

INDICATING MECHANISM FOR ROTARY HELICAL COOKERS.

1,406,213.

Specification of Letters Patent. Patented Feb. 14, 1922.

Application filed January 11, 1921. Serial No. 436,590.

To all whom it may concern:

Be it known that I, NIELS NIELSEN, a citizen of the United States, residing at Pittsburg, in the county of Contra Costa and State of California, have invented a new and useful Improvement in an Indicating Mechanism for Rotary Helical Cookers, of which the following is a specification.

My invention relates to improvements in indicators for rotary helical cookers for cooking canned products wherein an indicator operates in conjunction with the rotary helical conveyor of said cooker to indicate the longitudinal and peripheral position of a designated can within said cooker.

The primary object of the present invention is to provide a new and improved indicator for indicating the position of a designated can or cans within said cooker.

A further object of the present invention is to provide a new and improved device of the character described adapted to sound an alarm just previously to the arrival of a designated can or cans at any predetermined position in said cooker.

In rotary cookers of this type the period of time required for the passage of a designated can is approximately thirtyfive minutes.

After starting a run of cans through the cooker it is essential that the arrival of the cans at the other end of said cooker, or, the time said cans begin to emerge, should be known in order that the operators for the next or successive stage of treatment should be prepared to receive them.

Or, during a continuous run of cans through the cooker, it is sometimes desired to run one or more cans of a different canned product through the cooker with the regular run. Owing to the difference in the product it is sometimes essential that the introduced or designated cans be subjected to the action of heat within the cooker for a lesser period of time than that required for full passage through said cooker.

The time of arrival of the beginning or ending of a continuous run, or the position of an introduced can or cans, peripherally or longitudinally, may be indicated by the improved indicator which I have disclosed in the drawings forming a part of the present specification wherein like characters of reference are used to designate similar parts

throughout the said specification and drawings, and in which:

Fig. 1 is a broken side elevation of a rotary helical cooker, partly broken away to disclose the rotary helical construction.

Fig. 2 is a broken end elevation;

Fig. 3 is a broken plan view of one end of said cooker disclosing my device applied thereto;

Fig. 4 is a rear view of the indicating means disclosing the manner in which the pawls rotate the same continuously in one direction;

Fig. 5 is a side elevation of Fig. 4 and

Fig. 6 is an enlarged broken sectional view disclosing the manner in which the indicator operating means is adjustably attached to the rotating element of the cooker.

Referring to the drawings the numeral 1 is used to designate the housing of a cooker within which is mounted the helical track 2 of the well known type. A drum 3 is provided with longitudinally disposed angles or flights 4 and is mounted upon a shaft 6 which carries a worm gear 7 operated by the rotation of a worm 8 on the shaft 9 in turn rotated by the pulleys 11.

Mounted upon the adjacent end of the housing 1 is a shaft 12 carrying a stationary indicator arm or pointer 14. A dial 16 is rotatably mounted upon the shaft 12 and provided with peripheral graduations 17 to indicate peripheral and longitudinal positions on the helical path, and also provided with teeth 18 and apertures 19 on the periphery thereof.

Also pivotally mounted upon the shaft 12 and between the dial 16 and the housing 1 are a pair of approximately oppositely disposed arms 21 connected by means of suitable connecting rods 22 to an eccentric 23 in turn rotatably mounted upon a cam formed upon a pin 25 which is rotatably and slidably mounted in a threaded collar 24 screwed into a bore 26 of a plate 27 attached to the shaft 6 of the drum 3. The cam has an arm 28 formed integral therewith, said arm being provided with a lug or pin 29 adapted to engage any one of a plurality of apertures 31 arranged adjacent the periphery of said plate 27.

A spring 32 is interposed between a head 33 on the inner end of the pin 25 and the collar 24 to normally retain said arm 28

in engaging relation with the plate 27 through the medium of the lug 29 and one of the apertures 31.

The pin 25 is provided at its outer end with a handle 36 by means of which said pin may be moved outward against the tension of the spring 32 to release said lug 29 from the aperture 31 and then rotated to reposition said arm 28, the purpose of which 10 will hereinafter be more fully set forth.

A pin 37 is also provided to detachably engage any one of the apertures 19 within the edge or periphery of the dial 16 and to close the contacts 38 to sound an alarm 39 15 during the rotation of said dial 16, said pin 37 and dial 16 thus constituting an adjustable alarm operating means.

In operation cans of canned products are fed to the delivery conveyor 41 disclosed in 20 Fig. 1 of the drawings, which feeds said cans into an entry port 40 and to the helical track 2 around which said cans are conveyed by the action of the flights 4 on the drum 3, emerging at the other end of the cooker 1, 25 or discharged through any one of a plurality of intermediate delivery ports, with which this type of conveyor is provided, one of such being shown at 42, and into a chute 43 which delivers said cans to a conveyor 44 30 which then conveys said cans away from the conveyor.

When the beginning or ending of a continuous run, or an introduced batch, of cans is inserted or enters the entry port 40 the 35 handle 36 and pin 25 to which it is attached, are withdrawn against the tension of the spring 32 which disengages the arm 28 from the plate 27 and the said handle is then rotated, with the can, until said arm 28 lies approximately midway between the connecting rods 22, in which position one of a pair of one way pawls 46, pivotally mounted upon the ends of the arms 21 and engaging the teeth 18 of the dial 16, is positioned at the 40 beginning of its operative stroke to rotate the dial 16.

The handle 36 is then released and the lug 29 of the arm 28 inserted within the nearest aperture 31 which corresponds to one of the 45 flights 4 on the drum 3. Simultaneously the dial 16 is rotated until the graduation marker "0" is opposite or under the stationary indicator arm 14.

The rotation of the drum 3 and worm gear 50 7 will then, through the arm 28, pin 29 and plate 27, rotate the pin 25 and cam thereon to oscillate the arms 21 and pawls 46 thereon to continuously rotate the dial 16 and thereby move successive graduations 17 under 55 said arm.

The longer graduations 17 on the dial 16 indicate the successive convolutions of the helical conveyor 2 while the intermediate 60 graduations and the arm 28 indicate the peripheral positions of a designated can in-

roduced or delivered into the entry port 40 at the time the indicator is set.

The helical positions indicated by the graduations 17 on the dial 16 being known, the position of any designated can is readily ascertained by reading the graduation under the indicator or arm 14.

To sound the alarm 39 just previously to the arrival of any designated can within the cooker, or the beginning or end of a continuous run of cans, the pin 27 is inserted within the aperture 19 in the periphery of the dial 16 which is slightly in advance of the graduation indicating that position. As the dial 16 rotates the pin 37 will engage and 75 close the contacts 38 and thereby sound the alarm 39 to warn the operator that the designated can, or the beginning or end of the continuous run of cans is approaching the predetermined position from which said can 80 or cans are to be removed from the cooker.

As the pawls 46 are being moved in the same direction but on opposite sides of the dial 16, it is evident that one pawl will always be in operative and engaging relation 85 with the teeth 18 of said dial 16 while the other pawl 46 is inoperative and on its return stroke. Therefore a substantially continuous rotation will be imparted to said dial whereby the longitudinal and peripheral position of a designated can within the 90 cooker may be determined.

Having thus described my invention what I claim as new and desire to secure by Letters Patent is:—

The combination with a helical cooker for cooking canned products and having intermediate delivery ports therein, of a rotatably mounted dial graduated peripherally to indicate various longitudinal and peripheral 100 positions of said cooker, said dial being provided with an annular ratchet; a stationary indicator mounted adjacent the dial; a pair of oppositely disposed pawls arranged to engage said ratchet; a cam mounted upon the 105 cooker and arranged to be normally rotated therewith and adapted for independent movement relatively to the cooker for adjusting purposes; connections mounted between the cam and the pawls for alternately 110 actuating said pawls to rotate the dial whereby the position of a designated can within the cooker may be determined; an electrically operated alarm having a circuit closing element mounted adjacent the dial; and 115 a pin arranged to be adjustably mounted upon the dial at any desired point upon the periphery thereof adapted to engage the circuit closing element to operate the alarm to warn an operator of the arrival of said designated can at a predetermined point within the cooker.

In witness whereof I hereunto set my signature,

NIELS NIELSEN,
